UNITED STATES PATENT OFFICE.

WILLIAM VOGEL, OF CHICAGO, ILLINOIS, ASSIGNOR TO THE VOGEL PETROLEUM HEATING COMPANY, OF SAME PLACE.

BURNER FOR TOPS OF STOVES.

SPECIFICATION forming part of Letters Patent No. 416,878, dated December 10, 1889.

Application filed March 16, 1887. Renewed July 31, 1889. Serial No. 319,260. (No model.)

To all whom it may concern:

Be it known that I, WILLIAM VOGEL, of Chicago, in the county of Cook and State of Illinois, have invented certain new and useful Improvements in Burners for Tops of Stoves; and I do hereby declare that the following is a full, clear, and exact description thereof, reference being had to the accompanying drawings, and to the letters of reference marked thereon, which form a part of this specification.

This invention relates to a novel burner for gas or liquid hydrocarbons, adapted to be placed upon the top of a cooking or other stove, whereby the stove may be heated by a burner of the kind mentioned without removing the grate and linings commonly present therein.

A burner embracing the main features of my invention comprises a shell or casting adapted to rest at its bottom over a hole in the stove-top and provided with a combustion space or chamber, and with an oil or gas inlet passage communicating with the said combustion-chamber. Said combustion-chamber is located at one side of the burner, and a passage is provided for the exit of products of combustion at the opposite side of the burner, so that the products of combustion will pass from the combustion-chamber horizontally beneath a vessel placed upon the burner or beneath a metal cover closing the open top thereof, and then pass downwardly through the exit-opening mentioned into the stove and out through the smoke-passage thereof.

In a preferred form of burner herein illustrated the burner is provided with a central air-heating chamber supplied with air through inlet-openings at the ends of the burner, and communicating with the combustion-chamber by a lateral passage. In this construction the products of combustion will be caused to pass over the top of and then downward around said chamber in their way to the exit-flue of the stove, thereby insuring the heating of the air before it passes into the combustion-chamber. The inlet-passage for gas or oil is preferably cast in or upon the walls of the said heating-chamber, so that said passages are also exposed to the action of the

heated products of combustion passing around the chamber, and the oil or gas therein is thereby highly heated before reaching the point of combustion. 55

I have illustrated in the accompanying drawings one form of burner intended more especially for burning gas, together with other burners adapted for burning petroleum or other liquid hydrocarbon. 60

In the said drawings, Figure 1 is a central vertical transverse section through the upper part of a cooking-stove and a burner thereon. Fig. 2 is a longitudinal vertical section of the burner shown in Fig. 1, taken upon line $x-x$ of said Fig. 1. Fig. 3 is a horizontal plan section of the burner shown in Figs. 1 and 2, taken upon line $x-x$ of Fig. 2. Fig. 3^a is a top plan view of the burner shown in Figs. 1, 2, and 3. Fig. 3^b is a vertical transverse section of the same, taken upon line $x-x$ of Fig. 3^a. Fig. 4 is a central vertical transverse section of another form of burner embodying my invention, together with the adjacent parts of a cooking-stove. Fig. 5 is a longitudinal section of the same, taken upon line $x-x$ of Fig. 4. Fig. 6 is a similar section taken upon line $y-y$ of Fig. 4. Fig. 7 is a fragmentary plan section taken upon line $x-x$ of Fig. 6. Fig. 8 illustrates in central vertical cross-section a burner more especially adapted for burning gas or vapor, but which may also be used for burning liquid fuel. Fig. 9 is a longitudinal section of the same, taken upon line $x-x$ of Fig. 8. Fig. 10 is a plan section taken upon line $y-y$ of Fig. 8. Fig. 11 is a central vertical section of still another form of burner embodying my invention. Fig. 12 is a plan view of one end of the same, with parts broken away to show the interior construction thereof. Fig. 13 is a plan view of a similarly-constructed burner of circular form. 70 75 80 85 90 95

As illustrated in the several figures of the drawings, A is the top plate of the stove; A', the front wall thereof; A², the rear wall of the fire-chamber; and A³ is the plate which forms the top of the oven and between which and the top plate A is the passage A⁴, leading to the smoke-pipe of the stove.

In the form of the device shown in Figs. 1, 2, and 3 the burner consists of a single shell or casting having vertical inclosing-walls B,

provided at its lower edge with horizontal flanges *b*, adapted to rest upon the top plate of the stove about the margins of the hole *a* therein. The top of the burner is closed when in operation either by a cover or by the cooking utensil or utensils placed thereon. As shown, the upper margins of said wall *B* are of the same size and shape as the hole *a* in the stove-top, so that covers and cooking utensils adapted to fit the stove may also be placed upon the burner when the latter is upon the stove. The particular burner illustrated in these figures is made of elongated form to fit the single elongated hole commonly present in cooking-stoves, and which is closed by a central removable plate and two circular covers. The top of the burner is shown in the drawings as closed by a cooking utensil, as indicated, for instance, by *C*; but it may be closed by the metal covers of the stove or by special cover made to fit thereon.

In the bottom or lower part of the burner, at one side thereof, is a depression or trough *D*, which forms the oil-receptacle of the burner, and within which is preferably placed a porous bed *E*, which may be made of fire-brick, pumice-stone, or other porous material, or of a refractory granular substance, such as sand.

At the middle of the burner, and extending longitudinally from end to end thereof, is an air-chamber *F*, which communicates with the external air at the ends of the burner by means of suitable inlet-openings *f' f'*, Fig. 2. At the middle of the top wall of the said air-chamber *F* is located a transverse oil-passage *G*, one end of which is bent or curved downwardly toward and extends to a point near the bottom of the trough *D*.

G' is the oil-supply pipe, which extends into the air-chamber *F* of the burner from one end thereof and is connected with the upper part of the oil-passage *G*. Over the oil-trough *D*, and between the air-chamber and the adjacent part of the wall *B*, is formed a combustion-chamber *H*, and between said air-chamber and wall *B*, at the opposite side of the burner, is a passage or opening *H'*, through which the flames and heated products of combustion from the combustion-chamber may pass downwardly through the bottom of the burner into the stove.

In the particular construction of the burner herein shown the several parts of the burner are cast in one piece, the several walls composing the parts being disposed as follows: The lower walls of the air-chamber *F* and of the oil-trough *D* are formed by a horizontal bottom plate *B'*, cast integral with the vertical wall *B* of the burner and forming a continuation of the rear part of said wall, as clearly shown in Fig. 1. The said wall *B'* is provided with a longitudinally-arranged vertical rib *b*, which serves to divide the oil-trough from the air-chamber. *B²* is a horizontal plate forming the top wall of the air-

chamber *F* and also cast integral with the side wall *B* of the burner, said plate *B²* being connected with the bottom plate *B'* by means of a vertical wall *B³*. Between said wall *B³* and the adjacent part of the vertical wall *B* of the burner is formed the passage *H'*, through which products of combustion from the combustion-chamber *H* may pass downwardly into the stove. At its margin adjacent to the combustion-chamber *H* the horizontal wall *B²* is provided with a depending flange *b'*, between which flange and the flange *b* is formed longitudinal slot or opening *f²*, through which air from the chamber *F* enters the combustion-chamber. At each end of the chamber *F* is a transverse wall *B⁴*, which extends entirely across the end of the burner and forms the end wall of the said chamber *F* and also the end walls of the passage *H'*, the combustion-chamber *H*, and the trough *D*. In its part within the air-chamber the wall *B⁴* terminates somewhat above the bottom plate *B'*, so as to form the inlet-opening *f'*, through which air enters the said chamber *F*. Said wall *B⁴* is connected at its upper margins with the horizontal top wall *B²*, which latter is extended at its ends at *b² b²* to the ends walls of the burner, said parts *b² b²* being preferably arranged in a plane above the main part of said wall *B²*. Outside of and parallel with the wall *B⁴* is another transverse wall *B⁵*, connected at its lower margin with the bottom plate *B'* of the burner and extending upwardly to a point near the lower surface of the horizontal wall *b²*, so as to leave an air-inlet opening *f'*, which communicates with the opening *f²* by the vertical passage *f³* between said walls *B⁴* and *B⁵*. The said wall *B⁵* is desirably provided with a sliding valve plate or damper *B⁶*, adapted to control the opening *f'*, and thereby enable the influx of air to the heating-chamber to be regulated as desired. The passage *G* is preferably cast integral with the top wall *B²* of the chamber *F* and extends transversely of the latter, and is provided with a downward extended tubular part *G²*, which opens at the bottom of the trough *D*, preferably below the bottom of the porous bed *E* therein, as clearly shown in Figs. 1 and 3. To support the said porous bed *E* above the bottom of the trough *D* and thereby afford a space beneath said bed through which the oil may freely flow from the passage *G'*, I have herein shown open metal frames *e e* as placed in said trough under the porous bed; but studs or projections cast upon the bottom of the trough or any other suitable means may be employed for this purpose.

The operation of the burner thus constructed is as follows: Oil is admitted through a flexible pipe *G³* or by other oil-duct to the pipe *G'*, by which it is conveyed to the passage *G*. Oil is delivered to said passage *G*, flows downwardly through the latter into the bottom of the trough *D*, in which it distributes itself, and, rising through the porous bed *E*, is burned at the top of the latter. The pro-

ducts of combustion from the combustion-chamber H pass horizontally over the top of the air-chamber F and then downwardly through the passage H', from which they pass 5 to the smoke-exit passage of the stove, as indicated by the arrows in Fig. 3^b. The burner is preferably placed in the stove with the trough D nearest the rear of the stove or the smoke-pipe thereof, so that the heated products 10 of combustion will pass beneath the air-chamber and oil-trough. By the passage of the heated products of combustion over the plate B² said plate and the walls of the passage G are highly heated, so that the oil is 15 delivered to the trough D at a high temperature. Any oil which may overflow from the trough D (as may occur when the burner is first started and combustion is comparatively slow by reason of the parts being cold) will 20 accumulate in the bottom of the chamber F, and will there remain until vaporized by the heat of the parts. Air entering the air-heating chamber F through the passages f f' f³ at the ends of the latter, as indicated by the 25 arrows, passes to the combustion-chamber above the porous bed through the slot f². The walls B' B² B³ of the chamber F are highly heated by the products of combustion passing over or around said chamber in the manner 30 described, so that the air within the chamber becomes highly heated before its passage to the combustion-chamber with the result of greatly facilitating the rapid and complete combustion of the oil. The air entering the 35 chamber is also heated to some extent by contact with the walls of the passages f³ f³.

Another, and for some reasons a preferable, construction in a burner embodying the main features of my invention is illustrated in 40 Figs. 3, 4, 5, 6, and 7. In this instance the burner consists of two separate parts or castings I and J, and is provided with an oil-trough D, a porous bed E, an air-chamber F, an oil-passage G, and a combustion-chamber 45 H, arranged and operating generally in the same manner as before set forth. The oil-passage G in this case is formed by a passage g, extending longitudinally of the burner at the side of the latter adjacent to the opening 50 H' and sloping from the outer end of the burner downward to the middle of the latter, and a transverse passage g', sloping from the front toward the rear of the burner and connecting such passage g with the trough D.

55 Two of said passages g are preferably employed, extending from each end of the burner to the cross-passage g', so that oil may be fed into the burner from either end thereof. The cross-passage g' in this instance passes 60 through the middle of the air-chamber F and divides the latter into two separate compartments. The upper part or casting I of the burner consists of a vertical wall of ring shape, and the top wall of the air-heating chamber F and the passages g g' are formed 65 by a plate I', cast integral with the said upper part I and extending from end to end of

the latter. The bottom part J of the burner consists, mainly, of a bottom plate J', forming the lower walls of the passages g g' and 70 the bottom of the air-chamber F and the trough D and having upon its side margins horizontal flanges J², which rest upon the top of the stove. The part I is fitted at its lower margins to the flange J², the parts being secured together, as shown, by screws or bolts j j, passing through lugs i upon the casting I and the flange J². The bottom plate J' is provided with parallel walls j² j³, which are connected with the walls j² j², and which form, 75 together with depending flanges i' i' upon the top plate I', the cross-passage g'. Vertical flanges j' j', arranged longitudinally of the burner at either side of the central passage g', form the inner walls of the trough D 80 and separate the latter from the chamber F. The end of the passage g' adjacent to the trough D is closed by a depending part I² of the plate I', which part reaches to a point near the bottom of the trough, so as to leave 85 a narrow slit or opening for the outflow of oil from the passage g' to the trough. Said part I² consists, as shown, of vertical side walls i², forming continuations of the flanges i' and an end wall i³, as clearly illustrated in Figs. 95 4 and 7. At the ends of burner the casting I is provided with depending flanges I³ I³, terminating somewhat above the bottom plate J', so as to form inlet-openings f⁴ for the influx of air to the chamber F. The passages g 100 are closed at their ends by walls j⁵, preferably cast upon the bottom plate J', and provided with holes j⁶, through which an oil-supply pipe G' may be inserted. In a burner thus constructed it is not necessary that a tight joint 105 should be made between the oil-supply pipe and the oil-passage of the burner, and a pipe G' may be thrust loosely through the holes j⁶ into either one of the passages g, and the oil dripping or flowing from the said pipe will run 110 downward to the center of the burner and thence into the oil-trough D through the transverse passage g'. The passage H' for the 115 exit of the products of combustion from the burner downwardly into the stove is in this instance formed between the flange j', constituting the outer wall of the oil-passages g g, and the adjacent portion of the wall I, and the heated products of combustion pass over or against the vessel or cover upon the burner 120 and the top of the air-chamber, and then downwardly through said passage H', so as to accomplish the heating of the walls of the chamber and the air therein in the same manner as before described.

I have shown the casting I as provided with a mica-covered opening I⁴ in its part adjacent to the combustion-chamber, whereby the condition of the flame within the burner may be observed without opening the latter.

It may be here remarked in connection with the form of burners shown in Figs. 1 to 7 that said burners are more especially intended for burning heavy oils or liquid hydrocarbons

having a relatively high flashing or vaporizing point, and not for burning a light hydrocarbon, such as gasoline. It is not intended, therefore, in these burners that the oil shall become vaporized before reaching the point of combustion and thereafter burned in the form of vapor, but the oil supposed to flow in a heated state into the oil-trough and to be there consumed.

10 In Figs. 8, 9, and 10 is shown another form of burner, which is adapted for use in burning both oil and gas or vaporized hydrocarbons. This burner is generally similar to that illustrated in Figs. 1, 2, and 3, and embraces 15 a casting M, provided with vertical side walls M', a bottom wall M², a partial top wall M³, and a side wall M⁴, located inside of and parallel with the front outer wall of the burner, these several walls forming a combustion-chamber H, an air-heating chamber F, and an outlet-passage H' for the downward passage 20 for the products of combustion to the smoke-exit passage of the stove. At the side of the chamber F adjacent to the combustion-chamber is formed a longitudinal trough N, which 25 trough is arranged over a longitudinal slot h, by which air from the chamber F passes into the combustion-chamber H. An oil or gas supply pipe N' is inserted through the end 30 wall of the burner and opens into the space of the air-chamber at a point above the trough N. Upon the bottom wall M² of the burner and extending beneath the trough N is an oil-trough D, provided with a porous 35 bed E, said trough D being used when oil is used as a fuel. A rib or flange m divides the trough D from the main part of the chamber F. Air is admitted to the air-chamber F at the ends of the burner through a tortuous 40 passage f⁵, formed in the casting M, as clearly shown in Figs. 1, 2, and 3. In the use of this form of burner with oil, however, the oil delivered through the pipe N' flows into the trough N and becomes distributed therein 45 throughout the entire length thereof. When the trough has become filled, the oil overflows therefrom and drips into the trough D and is burned at the top of the porous bed therein. The trough N is preferably formed 50 integral with the adjacent top wall M³ of the chamber F, being connected with said top wall by a connecting part m', Fig. 8, which forms one wall of the combustion-chamber, so that the parts become heated, the oil will be 55 held at a high temperature, and will burn rapidly and with an intense heat when it reaches the porous bed. When this burner is used for burning gas or vapor, the gas flowing into the chamber F through the pipe N becomes mixed with air within said chamber 60 and burns at the narrow passage h. When the burner is used for gas or vapor, the porous bed E is obviously not required.

65 Figs. 11, 12, and 13 show a burner embodying the main features of construction present in the burners hereinbefore described, but differing therefrom in several particulars. In

this instance the body of the burner consists of a single casting L, having side walls and a partial bottom open at its top and made of the proper shape at its lower margin to fit the hole in the stove-top. The burner shown in Figs. 11 and 12 is made of oval form and adapted to fit over the large hole in a stove-top, while that shown in Fig. 13 is circular 75 and adapted to be placed over one of the single round holes of a stove. The casting L is shown as provided with a rabbet 1 about the margins of its lower edge, fitting the rabbeted margins of the hole in the top plate, as clearly 80 shown in the drawings. The open top of the casting L may be closed by the presence thereon of a vessel or cooking utensil, as indicated at K; but it may be provided with metal covers such as are commonly employed 85 on stoves, and for this purpose its upper margins are shown as made to correspond in size and shape with the hole in the stove to which the bottom of the burner is fitted, so that when the covers are removed from the stove 90 they may be placed upon the top of the burner. In the bottom or lower part of the casting L, adjacent to one of its sides, is an oil-trough D, within which is a porous bed E. In the casting between the bottom of said trough D and the lower horizontal surface of the casting is formed a chamber or recess L', communicating with the said trough D by means of passages l'. An oil-supply pipe G' communicates by passage l² with the interior of the 95 said recess L', whereby oil is fed to the said recess and to the trough D, which it enters by passing through the apertures l' l'. The recess L' extends from end to end of the burner, is preferably arranged to occupy the entire 100 space beneath the troughs D, and the oil is desirably fed to the central portion of said recess by extending the passage l² through a wall or partition l³, reaching from the end of the casting to a point near the middle of the 105 recess, as clearly shown in Fig. 12.

F indicates an air-heating chamber arranged longitudinally of the burner near the middle of the latter and at one side of the trough D, said chamber being provided at one 110 end with openings f f for the admission of air thereto, and having at its side adjacent to the trough D a longitudinal slot or opening l⁴, by means of which air for supporting combustion passes from the air-heating chamber to 115 the combustion-chamber H, located over the oil-trough. The inlet air-openings f f to the chamber F are controlled by a damper, herein shown as consisting of a revolving plate O, apertured to correspond with the openings f f, 120 and provided with a handle o, by which it may be turned. The opening l⁴ may be, if desired, provided with a sliding plate l⁵, whereby the size of the said opening may be increased or decreased, as found necessary or 125 desirable for the proper working of the burner.

When the burner is placed upon the stove and its top is closed by placing thereon a vessel or suitable cover, the operation of the de-

vice is as follows: Oil supplied through the pipe G' enters the chamber or passage L', the walls of which are kept at a high heat during the operation of the burner, so that said oil is heated before its passage into the trough D. Air for supporting combustion enters the chamber F, becomes heated therein, and then passes through the opening l⁴ into the combustion-chamber. The products of combustion making their exit from the combustion-chamber F pass over the air-chamber, downward between the side of the air-chamber and adjacent sides of the casting L, and then into the smoke-passage A⁴ of the stove. The burner is preferably placed upon the stove with its side containing the oil-trough D nearest the exit smoke-passage of the stove, so that products of combustion pass around the heating-chamber in the manner described, then pass around said chamber and beneath the trough D and oil-chamber L', and the heated gases and products of combustion act upon the bottom surface of said casting, and thereby greatly aid in the heating of said air-chamber and of the part of the casting containing the said passage L'.

The general construction described is the same either in the case of the long burner shown in Figs. 10 and 11, or in that of the round burner illustrated in plan view, Fig. 12.

I claim as my invention—

1. A burner consisting of a ring-shaped casting or shell adapted to fit at its lower

edges upon a hole in the top of a stove and having at its top a hole or holes for cooking utensils, a centrally-arranged air-heating chamber located within the said casting or shell, an oil-holding trough located between one side wall of the chamber and the shell, and the said chamber being provided with a slot or opening for the admission of air from the chamber to the main trough, and the side wall of the chamber opposite the said trough being constructed to constitute one side of an opening or passage leading downwardly through the shell or casting to the space between the stove upon which the burner is placed, substantially as described.

2. A burner comprising a casting or shell provided at its top with a hole for cooking utensils, and with a bottom wall having an exit-opening at one side for products of combustion, a central air-chamber, an oil-holding trough located at the side of said air-chamber opposite the exit-opening, and an oil-supply passage formed in and by the walls of said air-chamber, substantially as described.

In testimony that I claim the foregoing as my invention I affix my signature in presence of two witnesses.

WILLIAM VOGEL.

Witnesses:

C. CLARENCE POOLE,
CHARLES T. LORING.
